(57) **CLAIM**

The ornamental design of a clothes dryer, as shown and described.

DESCRIPTION

FIG. 1 is a front elevation view of an embodiment of a clothes dryer, showing our new design;

FIG. 2 is a back elevation view thereof;

FIG. 3 is a left elevation view thereof;

FIG. 4 is a right elevation view thereof;

FIG. 5 is a top plan view thereof;

FIG. 6 is a bottom plan view thereof;

FIG. 7 is a front right perspective view; and,

FIG. 8 is a front left perspective view.

The broken lines form no part of the claimed design.
